UNITED STATES PATENT OFFICE.

ROMAN F. POLSKI, OF ST. PAUL, MINNESOTA.

IRONING-BOARD.

1,158,279.

Specification of Letters Patent.

Patented Oct. 26, 1915.

Application filed March 6, 1915. Serial No. 12,513.

To all whom it may concern:

Be it known that I, ROMAN F. POLSKI, a citizen of the United States, residing at St. Paul, in the county of Ramsey and State of Minnesota, have invented a new and useful Improvement in Ironing-Boards, of which the following is a specification.

The primary object of this invention is the production of an ironing board, which is particularly adapted for use for pressing clothes in such manner as to absorb steam generated by a hot iron pressing the clothes and for preventing shiny or polished surfaces being produced on the material by the pressing iron.

Further objects of the invention are to provide the surface of the ironing board with a cushion, which will prevent breaking of buttons by the pressing iron, and also provide effective means for detachably securing a number of removable covers over the surface of the board, whereby a soiled or worn cover can be removed leaving a fresh cover exposed for use.

In the accompanying drawing forming part of this specification, Figure 1 is a plan of my invention, part of the structure being broken away; Fig. 2 is a section of a detail, and Fig. 3 is an edge elevation of my invention.

In the drawing, A indicates the back of the ironing board, which is made of convenient shape and of any construction for pressing purposes. The outer edge of this board is curved at the ends, and said edge is formed with a downwardly and inwardly inclined shoulder 2 distanced below the surface 3 of the back. Placed over the surface of the back is a flexible permanent cover 4 made of cloth or other suitable flexible material, said cover being stretched over a filling 5 of sawdust or other suitable disintegrated material forming a cushion and capable of readily absorbing steam, said material being spread out over the entire surface of the board and held firmly compressed by said cover. The edge of the cover conforms to the outer edge of the board, and is turned down over its edge.

and below its shoulder 2, said turn down portion being formed with a seam 6 containing a wire band 7, which tightly embraces the board and draws the material in, holding the cover stretched over the filling material and preventing the saw dust with-

in passing out. The edge of the cover is also secured at the edge of the board by fasteners 8, which are driven into the edge of the board immediately above the band 7, each of said fasteners being formed with a head 9. Stretched over the surface of the permanent cover 4 are a plurality of removable covers such as 10 and 11, each of which is formed with button holes 12. These removable covers have their edges 65 turned down and gathered at the ends over the edge of the ironing board and are detachably engaged by the pockets thus formed by gathering and by their button holes over the heads 9 of the fasteners 8. By this means the removable covers can be removed or replaced from time to time when desired.

In use the material to be pressed is placed over the board and a damp cloth arranged over the surface of the material in the usual manner. During the ironing operation, which follows, steam generated by the hot iron coming in contact with the wet or damp cloth passes through the material to be ironed and is absorbed by the saw dust. This action prevents objectionable polished and shiny surfaces on the material. The wood saw dust employed may be made from soft pine wood or other suitable material, the object being to provide a disintegrated substance, which will quickly absorb steam, and which has the quality of performing the function of a cushion to prevent buttons and like objects from becoming broken during the ironing operation, said filling material readily compressing to accommodate protrusions from the material and allowing the iron to pass smoothly over the material and the buttons. Wood saw-dust accomplishes these results most effectively, as it is of a spongy nature and packs with sufficient firmness to withstand ordinary ironing.

In accordance with the patent statutes, I have described the principles of operation of my invention, together with the apparatus which I now consider to represent the best embodiment thereof, but I desire to have it understood that the construction shown is only illustrative, and that the invention can be carried out by other means and applies to uses other than those above set forth within the scope of the following claims.

Having described my invention, what I claim as new and desire to protect by Letters Patent is:—

1. An ironing board, comprising, in combination, a back; a flexible cover over said back and a filling of wood saw-dust held by said cover over said back.

2. An ironing board, comprising, in combination, a back, a flexible permanent cover over said back, said back being formed with a shoulder on its edge below its surface and said cover having a band in its edge engaged below said shoulder, fasteners securing the edge of said cover to the edge of

said back, a removable cover stretched over the surface of said permanent cover and detachably secured to said fasteners and a filling of disintegrated readily absorbent cushioning material interposed between the surface of said back and said permanent cover.

In testimony whereof, I have signed my name to this specification, in the presence of two subscribing witnesses.

ROMAN F. POLSKI.
